CLAIM

I claim the ornamental design for a combination mailbox and newspaper receptacle, as shown.

DESCRIPTION

FIG. 1 is a front perspective view (from above left);

FIG. 2 is a front perspective view (from above right, with mailbox door ajar);

FIG. 3 is a rear perspective view (from below left); and,

FIG. 4 is a front side view (with mailbox flag in raised

position).

The surfaces or portions of the article not shown in the drawing or described in the specification form no part of the claimed design.
